No. 766,528.

PATENTED AUG. 2, 1904.

W. ROMUENDER & E. J. FELLMAN.
SWINGING SCREEN HANGER AND FASTENER.

APPLICATION FILED SEPT. 10, 1903.

NO MODEL.

UNITED STATES PATENT OFFICE.

WILLIAM ROMUENDER AND EDWARD J. FELLMAN, OF MILWAUKEE,
WISCONSIN.

SWINGING SCREEN HANGER AND FASTENER.

SPECIFICATION forming part of Letters Patent No. 766,528, dated August 2, 1904.

Application filed September 10, 1903. Serial No. 172,623. (No model.)

To all whom it may concern:

Be it known that we, WILLIAM ROMUENDER and EDWARD J. FELLMAN, citizens of the United States, and residents of Milwaukee, in the county of Milwaukee and State of Wisconsin, have invented certain new and useful Improvements in Swinging Screen Hangers and Fasteners; and we do hereby declare that the following is a full, clear, and exact description thereof.

Our invention relates especially to swinging screen hangers and fasteners in connection with window-frames; and it consists in certain peculiarities of construction and combination of parts, as will be fully set forth hereinafter in connection with the accompanying drawings and subsequently claimed.

In the drawings, Figure 1 is a vertical sectional view of a window-frame and swinging half-screen embodying our present invention, taken on the plane indicated by the line 1 1 in Fig. 3, showing in full lines the screen covering the lower half of the opening of the window-frame and in dotted lines indicating the screen reversed and attached, so as to cover the upper half thereof. Fig. 2 is a sectional view, taken on the planes indicated by the line 2 2 in Fig. 3; and Fig. 3, a view in elevation with the window-frame in vertical section on the plane indicated by the line 3 3 in Fig. 1 and looking outwardly from the inside of the apartment containing said window-frame.

Referring by numerals to the said drawings, 1 represents the bottom portion, 2 the top portion, and 3 4 the vertical side portions of the window frame or casing provided with the usual vertical guide-strips 5 6 7 on each inner side and with the upper horizontal guide-strips 8 9 10, thereby leaving spaces to receive the edges of the upper window-sash 11 and lower window-sash 12 between them.

The screen illustrated comprises a rectangular frame 13, with an inwardly-extending lateral strip 14 at one end, (the upper end in the normal position of the screen shown in the drawings where same is applied to cover the lower part of the window-frame opening,) and at this end the screen-frame is further provided with two shouldered hooks, constitut-

ing the hangers for the same, and at the opposite end (herein the lower end of the frame) with a revoluble handled catch 19, which engages with a suitable projection on the window-frame to lock the screen-frame thereto. These hangers in their preferred form here- 55 in illustrated are represented as being made of wire and comprise a vertical shank 15, with a projecting prong 16 at one end and an obliquely-disposed doubled hook 17 at its other end, said doubled hook extending away from 60 its shank in a direction opposite to the projection of the prong, with the outer bend of the said hook coming practically at its extreme end in line with said shank, and this doubled end thus in the position of the screen 65 shown in Fig. 1 extending over the lateral strip 14 of the screen-frame, while the prong 16 is driven into the adjacent end piece of the screen-frame 13 and preferably further held in position by a staple 18, driven into said end 70 piece below the lateral strip 14. At the other end of the screen-frame 13 the said catch 19 is pivotally held in place by a screw 20 on whose shank it can be revolved by means of the catch-handle 21, and said catch is adapted 75 for engagement at the proper time with a projection 22, secured to the bottom portion 1 of the window-frame, or with a like projection 23, secured to the upper horizontal guide 8 when the screen-frame is reversed, as hereinaf- 80 ter described. The screen proper, 24, preferably of wire mesh, is held to the rectangular screen-frame 13 in any suitable manner, as by the rectangular holding-frame 25. The op- 85 posed vertical guide-strips 5 5 are each pro- 90 vided with two headed pins 26 27, and the hanger-hooks 17, with their attached screen-frame, are suspended from the upper pins 26 26 when the screen is used for closing the lower half of the window-frame opening, 90 while if the said screen is reversed to close the upper half then the said hanger-hooks are engaged with the lower pins 27 27, and when the screen is raised up the catch 19 can be fas- 95 tened to the described upper projection 23, as clearly indicated by the dotted lines in Fig. 1.

The operation of our device will be readily understood from the foregoing description of

its construction, taken in connection with the drawings. In hanging the screen-frame 13 to occupy the position shown in full lines in the drawings the screen-frame is held nearly horizontally, but with the transverse outer edge on a higher plane than the inner edge and with the lateral strip 14 pointing downwardly and with the hanger-hooks between the pins 26 and 27 at each side with the lateral strip 14 (which is of less length than the end piece of the screen-frame to which it is attached) between the opposed side faces of the guide-strips 5 5 and with the end edges of the adjacent end piece (which project beyond the ends 15 of said lateral strip 14) in contact with the outer faces of the said guide-strips 5 5. In this position a slight upward movement of the thus-contacting end of the screen-frame 13 will serve to carry the now upwardly open ends 20 of the hanger-hooks up to the upper pins 26 26, with which said open (doubled) ends of said hooks instantly engage, forming a hinge connection, and then the operator releases hold of the screen-frame, which instantly drops 25 by gravity to place and can be fastened by a turn of the catch 19, which thus engages with the lower projection 22. If the screen-frame is designed to close the upper half of the window-frame opening, the said screen-frame is detached by lifting its lower end until it is again nearly horizontal, and an inward push of the screen-frame will instantly release the engagement between the hanger-hooks and pins 26 26 and the said screen-frame can be pulled 30 away and vertically reversed (with the wire-mesh 24 always on the outer surface of the screen-frame 13) and then brought to a practically horizontal position with the lateral strip 14 now uppermost and with the ends of the 35 adjacent top piece of the screen-frame against the outer surfaces of the guide-strips 5 5 and with the hanger-hooks between the pins 26 27, but with the doubled ends 17 of the said hooks now open downwardly, and in this position the screen-frame is guided by contact with the strips 5 5 downwardly until in a moment engagement is made between said hooks and the lower pins 27 27, forming a hinge connection, and the screen-frame is swung upward 40 thereon and fastened by engagement of the catch 19 with the upper projection 23. The said catch 19 is rounded on its inner edge, so that a very tight cam-lock is effected by its engagement with the straight edge of the 45 projection 22 or 23 and the screen-frame thereby held securely in either position to which it has been adjusted, and by reason of the shoulder or oblique bend of the hanger-hooks all danger of the screen-frame being 50 raised, pushed, or otherwise disconnected from the hinged connection is obviated in the movement of the upper window-sash or in handling an awning or outside blind or shutter if such are connected to the window-frame.

While we prefer to make the hangers of 65 wire, as shown, this is not material, as same may be made of sheet metal or of metal castings; but the described oblique shoulder is a necessary feature of their construction.

Having thus described our invention, what 70 we claim as new, and desire to secure by Letters Patent, is—

1. The combination with a window-frame, and opposed vertical inner guide-strips secured thereto, of upper and lower pins, projecting from each guide-strip, one above and one below the transverse center thereof, on each side; a pair of projections, one secured to the inner surface of the bottom portion, and the other to the inner surface of the top 80 portion, of said window-frame; and a vertically-reversible screen, having hangers with obliquely-disposed doubled hooks at one end of its frame, for engagement with either the upper or lower series of said pins, and a rev- 85 oluble catch at the other end of its frame, for engagement with one or the other of said window-frame projections.

2. The combination with a window-frame, and opposed vertical inner guide-strips se- 90 cured thereto, of pins projecting toward each other from the said guide-strips; a swinging screen-frame, having a lateral strip at one end, of a length less than the width of said screen-frame, and adapted to fit snugly be- 95 tween the opposed faces of said inner guide- strips, the adjacent projecting end edges of said screen-frame being adapted to bear against the outer faces of said guide-strips; and a pair of hanger-hooks formed with ver- 100 tical shanks secured to said screen-frame, and having oblique-shouldered open doubled ends for engagement with said pins, forming a re- 105 movable hinge connection therewith, the said obliquely-disposed doubled hook ends project- 110 ing and extending entirely and only over the said lateral end strip of the screen-frame, and with the extreme free end of each of said dou- 115 bled hook ends bent upward above the plane of the part of said hook end which is next the said vertical shank, whereby all danger of the said screen-frame becoming accidentally disconnected from said pins in the manipulation of said screen-frame, or in the movement of the devices connected or attached to said 120 window-frame, is obviated.

3. The combination with a window-frame, and opposed vertical inner guide-strips se- 125 cured thereto, of pins projecting toward each other from the said guide-strips; a swinging screen-frame having a lateral strip projecting inwardly from one end thereof, between the said guide-strips; and a pair of hanger-hooks in engagement with said pins, each hanger- hook having a vertical shank with a project- 130 ing prong at one end and an obliquely-dis- 135 posed doubled hook at its other end, the said prong entering the end of the screen-frame,

and said doubled hook projecting away from its shank in a direction opposite to the projection of the said prong and extending over said lateral strip, with the outer bend of the 5 said hook coming practically, at its extreme end, in line with said shank.

In testimony that we claim the foregoing we have hereunto set our hands, at Milwaukee, in

the county of Milwaukee and State of Wisconsin, in the presence of two witnesses.

WM. ROMUENDER.
EDWARD J. FELLMAN.
